UNITED STATES PATENT OFFICE.

WILLIAM McCLELLAN, OF FORT WAYNE, INDIANA.

DESIGN FOR A TAIL-COVER.

SPECIFICATION forming part of Design No. 31,285, dated July 25, 1899.

Application filed June 10, 1899. Serial No. 720,091. Term of patent 7 years.

To all whom it may concern:

Be it known that I, WILLIAM McCLELLAN, a citizen of the United States, residing at Fort Wayne, in the county of Allen and State of Indiana, have invented and produced a new and original Design for Tail-Covers, of which the following is a specification, reference being had to the accompanying drawing, forming part thereof.

10 The drawing is a perspective view of a tail-cover, showing the particular form of my new design, the leading or material features of which consist in the continuous gradual uniform curvature of the pouch 1, which curvature ranges from the lower end of said pouch to the end of the extension 2, and the straps 3, which extend from the end of said extension, range laterally in relation thereto.

Having described my invention, what I claim as new, and desire to secure by Letters 20 Patent, is—

The design for a tail-cover, as herein shown and described.

In testimony whereof I affix my signature in presence of two witnesses.

WILLIAM McCLELLAN.
